(57) **CLAIM**

The ornamental design for a foldable kitchen unit, as shown and described.

DESCRIPTION

FIG. 1 is a perspective view of the foldable kitchen unit of the present invention in the closed or folded position;

FIG. 2 is a perspective view of the foldable kitchen unit of the present invention in a partially opened position;

FIG. 3 is a perspective view of the foldable kitchen unit of the present invention in a partially opened position as shown in FIG. 2 with a portion of the top and sides of the unit partially removed to show additional detail of the stove top, sink and counter areas;

FIG. 4 is a perspective view of the foldable kitchen unit of the present invention in a fully opened position;

FIG. 5 is a perspective view of the foldable kitchen unit of the present invention in a fully opened position as shown in FIG. 3 with a portion of the top and sides of the unit partially removed to show additional detail of the stove top, sink and counter areas;

FIG. 6 is a front elevation view of the foldable kitchen unit of the present invention in a fully opened position;

FIG. 7 is a rear elevation view of the foldable kitchen unit of the present invention in a fully opened position;

FIG. 8 is a top plan view of the foldable kitchen unit of the present invention in a fully opened position;

FIG. 9 is a bottom plan view of the foldable kitchen unit of the present invention in a fully opened position;

FIG. 10 is a left side elevation view of the foldable kitchen unit of the present invention in a fully opened position;

FIG. 11 is a right side elevation view of the foldable kitchen unit of the present invention in a fully opened position;

FIG. 12 is a front elevation view of the foldable kitchen unit of the present invention in a fully closed or folded position;

FIG. 13 is a rear elevation view of the foldable kitchen unit of the present invention in a fully closed or folded position;

FIG. 14 is a right side elevation view of the foldable kitchen unit of the present invention in a fully closed or folded position; and,

FIG. 15 is a left side elevation view of the foldable kitchen unit of the present invention in a fully closed or folded position.
